UNITED STATES PATENT OFFICE.

GEORGE H. WIEGAND AND VIOLA E. WIEGAND, OF DENVER, COLORADO.

EAR PROTECTOR.

Application filed November 4, 1926. Serial No. 146,194.

This invention relates to an ear protector and has for its object to provide, in a manner as hereinafter set forth, a device of the class referred to, for preventing the accidental cutting of the ears of a person, especially ladies and children when bobbing their hair, and further whereby the device can be used as a protector to prevent injury to the ears of a person, by burning, while a head of hair is being marceled.

Further objects of the invention are to provide, in a manner as hereinafter set forth, an ear protecting device, which is simple in its construction and arrangement, strong, durable, compact, thoroughly efficient in its use, including inherent means for maintaining it in protective position with respect to the ears of a person, conveniently installed in position, and inexpensive to manufacture.

With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a side elevation of an ear protecting device, in accordance with this invention showing the adaptation thereof with respect to the head of a person and with the device in ear protecting position.

Figure 2 is a perspective view of an ear protecting device in accordance with this invention.

Figure 3 is a sectional plan thereof.

An ear protecting device in accordance with this invention comprises a pair of oppositely disposed protectors referred to generally by the reference characters 1, 2 and a pair of slidably connected resilient arms referred to generally by the reference characters 3, 4 and each of said arms has one of its ends fixedly secured to a protector. The resilient arms provide inherent means for retaining the protectors in position with respect to the ears of a person.

As both protectors are of like construction, but one will be described, as the description of one will apply to the other.

Each protector comprises an oval shaped cap member consisting of an oval shaped plate 5 formed integral with an inwardly extending continuous flaring flange 6, of the same contour as the contour of the plate 5. The flange 6 is cut away at its point of joinder with the plate 5, to form a passage or slot 7 disposed approximately at the transverse median of the plate 5. The slot 7 formed in the member 1 is provided for the passage of the arm 3 which extends partly across the inner face of the plate 5, bears against said inner face and is fixedly secured therewith by a holdfast device 8. The slot 7 formed in the protector 2 is provided for the passage of the arm 4. The arm 4 is secured to the protector 2, in the same manner as the arm 3, is secured to the protector 1. The forward ends of the arms 3 and 4 extend through the slots 7 and the rear end of each of said arms is in the form of a band. The band on the arm 3 is indicated at 10 and the band on the arm 4 at 11. The bands are oppositely disposed with respect to each other and provide means for slidably connecting the arms 3 and 4 together. The connecting of the arms 3 and 4 together in a manner as stated provides for the adjusting thereof relatively to each other. The arms 3 and 4 provide a resilient holder for maintaining the protectors in position with respect to the ears of a person, and owing to the manner of slidably connecting the arms 3 and 4 together, the holder is lengthwise adjustable.

The plate 5, of each protector, is formed with a series or row of spaced openings 12 providing air passages or for admitting sound so that the wearer of the device can hear. Each opening of the series or row of openings is positioned between the center of a plate 5 and the flange 6. The secured end of the arm 3 or 4 is positioned between a pair of openings of the series or row of openings.

When the device is mounted in position, the elements 1 and 2 are arranged to enclose the ears of the person, and the holder extends around the back of the head, see Figure 1. The flange 6 can be of any suitable width so that the protector will be of the desired depth. Each protector can be of any suitable width and length desired.

Owing to the adjustability of the resilient holder it can be adjusted to any headsize,

from a small child to an adult. The resilient arms 3, 4 are secured against the inner face of the plate 5, so as not to interfere with the shears during the cutting or bobbing operation of the hair. The normal tendency of the adjustable holder is to force the protectors 1 and 2 against the head of the person whereby said protectors 1 and 2 are maintained in position. The holder depends at a downward inclination with respect to the protectors 1 and 2 and in a manner as shown in Figure 1.

Each of the protectors are constructed of rigid material, preferably aluminum owing to its lightness, but it is to be understood that each protector can be formed of any suitable material.

It is thought that the many advantages of an ear protecting device, in accordance with this invention, can be readily understood, and although the preferred embodiment of the invention is as illustrated and described yet it is to be understood that changes in the details of construction can be had which will fall within the scope of the invention as claimed.

What we claim is:

1. An ear protecting device comprising a pair of oppositely disposed protectors, each consisting of a plate formed of rigid material and provided with an inwardly extending edge flange co-extensive with the plate and of flaring contour, said plate formed with a row of spaced openings and with each opening of the row positioned between the center of the plate and the flange, and a holder for said protector, said holder having each end thereof attached to a protector.
2. An ear protecting device comprising a pair of oppositely disposed oval shaped protectors, each consisting of a plate having an integral inwardly extending edge flange co-extensive therewith and of flaring contour, each of said plates formed with a row of spaced openings and with one side of its flange slotted, and a lengthwise adjustable resilient holder common to said protectors and having the ends thereof extending

through said slots and secured to the inner faces of the plate. 50

3. An ear protecting device comprising a pair of oppositely disposed oval shaped protectors, each consisting of a plate having an integral inwardly extending edge flange co-extensive therewith and of flaring contour, each of said plates formed with a row of spaced openings and with one side of its flange slotted, a lengthwise adjustable resilient holder common to said protectors and having the ends thereof extending through 55 said slots and secured to the inner faces of the plate, the secured ends of said holders positioned between the pairs of openings of said rows.

4. An ear protecting device comprising a pair of oppositely disposed oval shaped protectors, each consisting of a plate having an integral inwardly extending edge flange co-extensive therewith and of flaring contour, each of said plates formed with a row of 70 spaced openings and with one side of its flange slotted, a lengthwise adjustable resilient holder common to said protectors and having the ends thereof extending through said slots and secured to the inner faces of 75 the plate, said holder formed of a pair of slidably connected sections and the secured ends thereof positioned between pairs of openings of said rows.

5. An ear protecting device comprising a pair of protectors oppositely disposed with respect to each other and each consisting of a plate formed of rigid material and an inwardly extending edge flange integral and co-extensive with the plate, each of said plates 85 formed with a row of spaced openings, a pair of resilient arms slidably connected together, each of said arms extending through one side of a flange and partly across the inner face of a plate and between a pair of openings of 90 a row, and means for fixedly securing the arms to the plate.

In testimony whereof, we affix our signatures hereto.

GEORGE H. WIEGAND.
VIOLA E. WIEGAND.
